UNITED STATES PATENT OFFICE.

SINGLETON A. MAXWELL, OF NEW YORK, N. Y., ASSIGNOR, BY MESNE ASSIGNMENTS, TO THE MAXWELL AUTOMATIC FOLDING, WRAPPING & ADDRESSING MACHINE COMPANY, OF AUGUSTA, MAINE, A CORPORATION OF MAINE.

FEEDING MECHANISM FOR MAILING-MACHINES.

992,224.

Specification of Letters Patent. Patented May 16, 1911.

Application filed January 18, 1905, Serial No. 241,686. Renewed April 9, 1908. Serial No. 426,084.

To all whom it may concern:

Be it known that I, SINGLETON A. MAXWELL, a citizen of the United States, and a resident of New York, in the county and State of New York, have invented certain new and useful Improvements in Feeding Mechanism for Mailing-Machines, of which the following is a full, clear, and exact description, such as will enable those skilled in the art to which it appertains to make and to use the same, reference being had to the accompanying drawings, forming part of this specification.

This invention relates to improvements in mailing machines, and more particularly in the machine disclosed in the application filed by me October 17, 1902, renewed June 25, 1908, and bearing Serial Number 440,359. In that machine the article to be wrapped is placed by hand upon the tapes of the feeding mechanism.

The purpose of the present invention is to provide a mechanism for automatically feeding the articles from a magazine in which they are stacked onto the tapes and thereby do away with the hand feed.

In practice the hand feed, especially when newspapers are wrapped, has been found to be too slow and the speed of the machine very much limited. In the present invention the newspapers are stacked in a magazine and mechanism is provided for withdrawing them successively from the magazine and depositing them on the tapes, so that the speed of the machine is only limited by the capacity of the wrapping mechanism proper.

The invention consists in the novel construction, combination and arrangement of parts, such as will be hereinafter fully described, pointed out in the appended claims, and illustrated in the accompanying drawings.

In the drawings, in which similar reference characters designate corresponding parts, Figure 1 is a longitudinal vertical section of a feed mechanism embodying the invention. Fig. 2 is a plan view of the same with parts broken away and omitted for the sake of clearness. Fig. 3 is an enlarged view showing a side elevation, broken away in parts, showing part of the operating mechanism. Fig. 4 is a similar view of the opposite side. Fig. 5 is a side elevation

of the jaw-mechanism for partly withdrawing the bottom paper from the magazine. Fig. 6 is a plan view of the same. Fig. 7 is a side elevation of the same showing the position of the jaws just after they have grasped a paper. Fig. 8 is a similar view showing the jaws just after they have released the paper. Fig. 9 is a transverse sectional view of the jaw-mechanism. Fig. 10 is a plan view of the magazine. Fig. 11 is a detail view showing the knee-lever and its connections for starting the machine. Fig. 12 is a detail view showing the tapes and the pulleys carrying the same. Fig. 13 is a detail view showing the eccentric pin for pivoting the yielding jaw.

The supporting frame of the feeding mechanism is of such a construction as to fit in with the main part of the frame disclosed in the application hereinbefore referred to.

Projecting from the front of the cross-piece 52 of the main frame of the machine are the extension frames or brackets 174 on the forward ends of which is the shaft 175 with its ends journaled in the bearings 176. On the shaft are secured the grooved pulleys 177. Over the latter and the sleeve 178 rotatable on the shaft 179 carried by the arm 180, on the inner ends of the brackets 174, are the twisted bands or tapes 181. On the sleeve 178, between the tapes, are the rubber collars 182 with corrugated peripheries. The shaft 175 is rotated by the sprocket-chain 183 engaging with the sprocket-wheel 184 on said shaft. The sprocket-chain is driven by the sprocket-wheel 185 on the rotatable shaft 186. The sprocket-chain passes over the idler sprocket-wheel 187 journaled on a sleeve 188 eccentrically mounted on a shaft 189 carried by the adjacent bracket 174. By adjusting the sleeve 188 any slack in the sprocket-chain may be taken up. The shaft 186 is rotated by the sprocket-chain 190 engaging with the sprocket-wheel 191 on said shaft and the sprocket-wheel 192 on the main driving shaft 57. Engaging with the sprocket-chain 190 is the idler sprocket-wheel 193 carried by the bracket 194 adjustably mounted on the cross-piece 52. By adjusting the bracket the tension of the sprocket-chain 190 can be regulated. By rotating the shaft 175 mo-

tion is given to the twisted bands or tapes and any article placed thereon will be fed toward the assembling mechanism of the machine. The twisted bands rotate the sleeve 178 and the collars 182 on said sleeve, so that the article engaged by the corrugated peripheries of the collars will be fed to the assembling mechanism.

In the uprights 195 on the inner ends of the brackets 174 is journaled the shaft 196 carrying the fingers 197 with their free ends turned upwardly. The shaft is rocked by the arm 198 on said shaft and connected by the link 199 with the upper end of the lever 200 pivoted at the lower end to the frame of the machine. (Dotted lines Fig. 3. Full lines Fig. 2). This lever is provided with a friction-roll 201 that engages with the cam 202, and through the action of which the lever is vibrated and consequently the shaft 196 is rocked. A spring 203 connected with the arm 198 works against the action of the cam 202 and normally holds the free ends of the fingers 197 in an elevated position in the path of travel of the articles carried by the twisted bands 181. These fingers form stops against which the articles are moved by the twisted bands, and hold them until the assembling mechanism is ready to receive them. The movement of the shaft 196 is timed to accord with the action of the assembling mechanism.

A longitudinal guide 204 is mounted at one side of the twisted bands 181. It is carried by the arm 205 horizontally adjustable on one of the standards 206. The twist in the bands is such as to move the articles against the longitudinal guide and the latter gives them their proper direction to the assembling mechanism. A spring finger 207 is provided for pressing the article against the twisted bands. The engaging end of the spring finger is serrated, and it acts as a pawl to prevent the articles from rebounding when they strike the stops 197. This finger is carried by the arm 208 secured on the longitudinal guide 204. The latter can be adjusted to accommodate articles of different widths.

50 A roll 209 is journaled on the shaft 210 secured in the free ends of the arms 211 pivoted on the rock shaft 196, and operates to press the articles onto the rubber collars 182 as they are released by the fingers 197. The 55 roll is raised intermittently by the lever 212 pivoted on the shaft 196, and having at the upper end a slotted arm 213. Through the slot in the arm 213 passes the screw 214 into the adjacent arm 211. By tightening the 60 screw the two arms 211 and 213 can be secured together. On the lower end of the lever 212 is the friction-roll 215 engaging with the cam 216 on the shaft 186. As the cam rotates the lever is oscillated, and 65 through its connection with the arm 211 the

roll 209 is intermittently raised and lowered. The operation of the cam is such as to lower the roll 209 when the article passes beneath it after being released by the stop 197 to press the same upon the collars 182, and thereby insures a correct feed of the article to the assembling mechanism. After the article has passed to the assembling mechanism the cam operates to raise the roll 209 just before another article is released by the stops 197. By means of the slotted arm 213 and the screw 214 the distance which the roll will be raised and lowered can be regulated to accommodate articles of different thicknesses. Up to this point the construction of the feeding mechanism is quite similar to the feeding mechanism disclosed in the said application. It is well adapted to feeding to the assembling mechanism articles placed singly thereon by hand. The speed at which it can be operated depends upon the skill of the operator in placing the articles singly upon the tapes. This has been found to be too slow for practical purposes when such articles as newspapers are prepared for mailing. That part of the invention hereafter to be described relates to an automatically operated mechanism particularly adapted to feeding newspapers from a stack placed in a magazine for holding the same. While it is particularly described as being adapted to feeding newspapers, yet it can be used for feeding other articles.

Gripping rolls are provided for engaging with the newspaper as it leaves the magazine (hereinafter described) to move the same onto the tapes 181. On the shaft 175, between the grooved pulleys 177, are secured the lower rolls 217. These rolls are of the same diameter as the pulleys and, consequently, their peripheral speed is the same as the speed of the tapes. Immediately above the rolls 217 are the upper rolls 218 secured on the shaft 219 journaled in the free ends of the swinging hangers 220 and 221 respectively, secured on the ends of the shaft 222 journaled in the standards 206. Springs 223 connected with the frame of the machine and the hangers force the free ends of the latter downwardly. The hanger 220 is in the form of a triangular frame, and at the lower end is a friction-roll 223^a bearing on the cam 224 on the shaft 186. The rotation of the cam oscillates the hangers 220 and 221 against the action of the springs 223, and thereby moves the upper rolls 218 relatively to the lower rolls 217. The relative movement of the rolls is timed so that they will come together to engage the article just as it leaves the magazine and so that they will separate after the article is fed onto the tapes. The shaft 219 is rotated by the train of gears 225, the upper one of which is secured on said shaft and the lower

one meshes with the gear 226 on the shaft 175. The dimensions of these gears are such as to drive the rolls 218 with the same peripheral speed as the rolls 217. The teeth 5 of the lower gear 225 and the gear 226 are of such a length as to engage with each other during the movement of the hanger 220.

On the extreme outer ends of the frames 174, and elevated somewhat above the same, 10 is mounted the magazine for holding the stack of newspapers. The base or floor 227 of the magazine is supported at its four corners by the brackets 228 carried by the posts 229 secured on the frames 174. Standards 15 230 are adjustably mounted on the base by the screws 231 passing through their slotted lower ends. These standards are on three sides of the base. On the fourth or 20 inner side the posts 229 are continued above the base, and vertically adjustable thereon are the cross-pieces 232. Horizontally adjustable on the cross-pieces are the four 25 stops 233, the inner faces of which are flush with the front edge of the base. By adjusting the standards 230 relatively to each other and to the stops 233, the magazine can be regulated to accommodate newspapers of different sizes. In the front 30 edge of the base in the recess 234 and projecting into the same from opposite sides, are the plates 235 with an opening or throat 236 between them leading into said recess. The tops of these plates are flush with the 35 upper surface of the base and their forward ends, as at 237, project beyond the edge of the base to form spring supports. On the lower ends of the two inner stops 233 are presser-feet 238 of the same outline as the supports 237. These stops are 40 adjusted horizontally on the cross-pieces 232 so that the presser-feet come directly over the supports 237; the stops are also vertically adjusted so as to permit only a single newspaper to pass beneath the presser-feet 45 with some little friction. The outer stops 233 are horizontally adjusted so that the edges of the newspapers in the stack will rest against the same, and vertically adjusted so that a single newspaper can pass freely 50 beneath their lower ends.

Mechanism is provided for drawing the bottom paper in the stack from the magazine to a position between the gripping rolls 217 and 218 so as to be engaged by the same 55 when they come together. Beneath the base of the magazine, and directly below the recess 234, is the guide or track 239, and movable back and forth on the latter is the carriage 240. To this carriage is pivoted one 60 end of the rod 241 by the wrist-pin 242. The other end of the rod is pivoted to the upper end of the lever 243 hinged at its lower end to the frame of the machine. On the lever 243 is a friction-roll 244 that 65 engages with an eccentric groove in the disk

245 on the shaft 186. As the disk rotates, through the intervening mechanism, the carriage is reciprocated on the guide-way.

On the rear end of the carriage 240 is pivoted the arm 246 by the pin 247. On the free end of the arm is pivoted the yielding jaw 248 by the pin 249. This jaw is bifurcated on its under side and straddles the arm. The two outer bearing surfaces 250 and 251, respectively, of the pin 249 on 70 which the members of the jaw are journaled are concentric to the main axis of the pin. (Fig. 18). The intermediate bearing surface 252 that is journaled in the arm 246 is eccentric to the main axis of the pin. By 75 turning the pin in its bearings the yielding jaw can be adjusted relatively to the arm. The pin is secured in its adjustment by the screw 253 passing through the end of the arm and impinging on the eccentric bearing 80 of the pin 249. The movement of the jaw on the pin is controlled by the screws 254 and 255 respectively, passing through the arm to engage with the jaw on opposite sides of its pivot 249. On the screw 254 is the 85 spring 256 bearing on the back of the jaw with a very slight pressure, and acts to normally hold the jaw in a horizontal position. The end of the arm 246 is slit, as at 257, adjacent to the holes of the screws 253 and 254. 90 By means of the screw 258 passing through the arm between the said holes the walls of the latter can be clamped together to secure the screw 254 in its adjustments. (Fig. 6).

On the arm 246, intermediate of its ends, 100 is mounted the lever 259. This lever is bifurcated and straddles the arm, and is pivoted thereon by the pin 260 passing through said arm and the members of the bifurcation. The upper or forward end of this lever 105 forms the movable jaw 261 coöperating with the yielding jaw 248. On the upper face of the movable jaw at its extreme forward end is the nose 262. The jaw end of the lever 259 is normally pressed upward 110 toward the yielding jaw by the spring 263 in the socket 264 working through the pin 265 movable in said socket and bearing on the under side of the jaw-end of the lever. At the lower or tail end of the lever 259, the 115 roll 266 is journaled between the ends of the members of the bifurcation. The pin 267 forming the journal for this roll projects from the side of the lever in a position to be engaged by the catch 268 when the 120 tail end of the lever is raised. This catch is pivoted on the pin 247, and is limited in its outward movement by the pin 269 on the lever 259. When the catch is in engagement with the pin 267, the jaw-end of the lever 125 259 is depressed against the action of the spring 263.

Means are provided for oscillating the lever 259 to move the jaw 261 relatively to the jaw 248, so that the said jaws can op- 130

erate to grasp a paper placed between them during the forward movement of the carriage 240, and to release the article when the carriage reaches the limit of its forward stroke. In the path of travel of the roll 266 the cam 270 is mounted on the guide-way 239. As the carriage 240 moves forward and approaches the limit of its stroke, the cam engages with the roll and raises the tail-end of the lever 259 against the action of the spring 263. As the carriage continues its forward movement the roll rides on the top of the cam and holds the tail-end of the lever in its raised position. While the roll is riding on the top of the cam the lower end of the catch 268 strikes the stop 272, and the catch is moved into engagement with the pin 267 at the time the carriage reaches the limit of its forward stroke. (Fig. 8). This raising of the tail-end of the lever opens the jaws 248 and 261 a short distance before the carriage reaches the forward limit of its stroke and releases any article that may have been seized by the jaws. As the carriage continues to the extreme forward limit of the stroke the jaws pass clear of the article. During the backward or return stroke of the carriage 240 the tail-end of the lever 259 is held in an elevated position by the catch 268. (Fig. 5). Consequently during this backward movement the jaws are open. Just before the carriage reaches the end of its backward stroke the pin or lug 271 strikes the stop 273 and the catch is disengaged from the pin 267. (Fig. 7). This frees the tail-end of the lever and the spring 263 is permitted to act to force the jaw 261 toward the opposing jaw 248 to seize any article between them. After the releasing of the lever the carriage starts on its forward movement, and the spring 263 continues to act to force the jaws together until the roll 266 engages with the cam 270.

The jaws 248 and 261 are carried by the pivoted arm 246. During the forward movement of the carriage 240 the free end of this arm is in a raised position. During the first part of the return or backward stroke of the carriage the arm is in a lowered position. The object of this is to enable the jaws to carry the article between the gripping rolls 217 and 218 during the forward movement of the carriage, and also to permit them to drop clear of the article on the return stroke of the carriage. Means are provided for raising and lowering the free end of the arm for this purpose. On the forward end of the carriage 240 is pivoted the dog 274 having wings 275 and 276. During the first part of the forward movement of the carriage the wing 275 rides over the top of the cam 277. This throws the wing 276 up against the under side of the arm 246 and holds the latter in an el-

vated position, which is horizontal. The jaws supported by the arm in this position travel so as to carry the article held by them between the gripping rolls. As the carrier advances in its forward movement, and the jaws release the article, the arm is still held in an elevated position until the jaws clear the article. (Fig. 8). As the carriage approaches the limit of its forward stroke the wing 275 of the dog strikes the stop 278 and the dog is turned so that the wing 276 is moved downward, and the free end of the arm 246 drops by its weight. The free end of the arm remains in its lowered position during the first part of the backward or return stroke of the carriage until the wing 275 engages the cam 277, and the dog is turned to raise the arm again. (Fig. 5). While the arm is in its lowered position, the jaws pass beneath the article they have just released. When the arm is raised again, the jaws will have cleared the article they have just released, and will be in position to engage with the succeeding article in the magazine. The upward movement of the arm 246 is limited by the wing 275 engaging with the adjacent pin 279.

It is to be observed that the stops 272, 273, and 278, and the cams 270 and 277 are adjustably mounted on the guide-way 239 so that they can be regulated to act at the proper time to perform their functions.

Means are provided for automatically stopping the machine should an article pass from the magazine to the gripping rolls 217 and 218 of a greater or less thickness than the article which the machine is adjusted to accommodate. To the lower inner end of one of the extension frames 174 is pivoted the arm 280 by the wrist-pin 281. (Fig. 4). On the same wrist-pin and inside of the arm is pivoted the lever 282. In the arm 280 is a slot through which passes the binding-screw 283 into the lever 282. By means of the binding-screw the arm and lever can be relatively adjusted and secured. The free upper end of the lever 282 is connected by the link 284 with the lower end of the pivoted frame 220. The lower free end of the arm 280 is bent inwardly, as at 285, so as to engage with the outwardly bent end 286 of the angular lever 287. (Figs. 1 and 2). This angular lever is pivoted on the shaft 288 journaled in the frame of the machine.

The shaft 288 carries the key 289 for operating the clutch mechanism 290 on the main driving shaft 57 for transmitting motion from the pulley 291 to the said main shaft. To oscillate the shaft 288 to move the key 289 to operate the clutch, an arm 292 is secured on the said shaft. (Figs. 2, 3 and 11). The lower end of this arm is connected by the rod 293 with the free end of the knee lever 294 pivoted to the outer

end of one of the extension frames 174. When the free end of the knee lever is moved inwardly, through the intervening mechanism, the key 289 is raised to permit 5 the two members of the clutch to engage and thereby transmit motion from the pulley 291 to the main driving shaft 57. On the shaft 288 is the catch 295 in a position to be engaged by the latch 296 pivoted to the 10 frame 52 of the machine. When the latch 296 is in engagement with the catch 295, the key 289 is held in a raised position so that the two members of the clutch 290 can engage.

15 On the main driving shaft is the cam-wheel 297 with the depression 298 in its periphery. On the lower end of the angular lever 287 is the roll 299, and the latter is normally pressed against the periphery of 20 the cam-wheel 297 by the spring 300 connecting said lever with the frame 52. Pivoted on the latch 296 is the dog 301 recessed at its lower end to engage with a pin 302 on the angular lever 287 and provided at its 25 upper end with a lug projecting over the latch 296. (Fig. 2.) When the roll 299 enters the depression 298 of the cam-wheel 297 the angular lever is oscillated so that the pin 302 engages with the lower recessed end 30 of the dog 301, and as the lever is rocked the latch 296 is raised by the dog 301 until the lug on the top of the dog engages with the top of the latch and disengages the dog from the pin 302. This releases the latch 35 and permits it to drop to an engaging position again. The upward movement of the latch 296 releases the catch 295 and the shaft 288 is freed so that the key 289 can descend to separate the members of the clutch 290 40 and thereby stop the machine. This stopping of the machine happens just after the roll 299 leaves the depression 298 and leaves the machine in an initial position to commence an operation. As shown and described in the former application, the shaft 45 288 also operates a brake mechanism to take up the momentum of the machine after the clutch members have been separated.

When the machine is in operation under 50 normal conditions the roll 299 cannot enter the depression 298. As the depression approaches the roll 299, the turned-out end 286 of the angular lever is engaged by the turned-in end 285 of the arm 280, and the 55 roll is prevented from entering the depression. Consequently the latch 296 will not be raised to release the catch 295, and the operation of the machine will not be checked. Should the two ends 285 and 60 286 not engage, then the roll would enter the depression, and the latch raised to disengage the catch and thereby permit the key 289 to drop to separate the clutch-members to stop the machine.

Before the machine is put in operation, 65 one of the articles is placed between the gripping rolls 217 and 218, the arm 280 is then adjusted relatively to the lever 282 so that its end 285 will be in the path of the end 286 of the lever 287. (Fig. 4). When an 70 article of average thickness is passing between the rolls 217 and 218, the upper rolls 218 will be raised to such an extent as to oscillate the hanger 220 as to move the arm 280 through the link 284 and the lever 282, 75 so that the end 285 of the arm will engage with the end 286 of the lever 287, and thereby prevent the roll 299 from entering the depression 298 to stop the machine.

Should an article thicker than the average 80 pass between the rolls 217 and 218, through the intervening mechanism, the arm 280 would be moved to a greater distance and its free end 285 would be raised clear of the end 286 of the angular lever. Consequently 85 the angular lever would be oscillated by the roll entering the depression and the machine thereby stopped. Also, should an article of less thickness than the average pass between the gripping rolls, the movement 90 of the free end of the arm 280 would pass beneath the end 286 of the angular lever and the latter, consequently, could operate to stop the machine. Should the machine 95 stop automatically, it would indicate that an article not of the average size had been fed onto the tapes and steps could be taken to prevent the same from passing into the wrapping mechanism.

Means are provided for stopping the machine by hand. (Fig. 1). To one of the side frames of the machine is pivoted the lever 303 connected with the latch 296 by the link 304. A spring 305 pulls downwardly on the free end of the lever 303, and 105 also acts to depress the free end of the catch 296. By means of the handle 306 the lever 303 can be moved against the action of the spring 305 to raise the latch 296 to release 110 the mechanism holding the key 289 so that the latter can fall to separate the clutch members.

The operation of the machine is as follows: The standards 230 and the stops 233 are horizontally adjusted on the base 227 115 of the magazine relatively to each other to accommodate the papers according to their superficial dimensions; and the stops 233 are vertically adjusted to accommodate the papers according to their thickness so that but 120 a single paper can pass beneath the lower ends of the stops. In adjusting the two inner stops 233 the presser-feet 238 are adjusted relatively to the spring supports 237 so as to exert a yielding pressure on the 125 paper as it passes between the same. The purpose of the presser-feet and opposing spring supports is to prevent the papers

from being drawn from the magazine until the gripper rolls 217 and 218 are brought into action. The papers are stacked in the magazine with their folded edges abutting 5 the stops 233, as shown in Fig. 1.

Previous to starting the machine, the jaws 248 and 261, and the gripping rolls 217 and 218, are respectively adjusted relatively to each other to accommodate the thickness of 10 the paper. The machine is put in motion by the operator pressing on the knee lever 294 to throw the members of the clutch 290 into engagement with each other. Through the intervening mechanism the carriage 240 carrying the jaws 248 and 261 is reciprocated in the guide-way 239 between the magazine and the gripping rolls. As the jaws move toward the magazine and pass into the 15 throat 236 between the plates 235, they engage with the bottom paper in the magazine; and when the jaws move away from the magazine they carry the paper between the gripping rolls.

At their folded edges the papers are not 20 of exactly the same thickness, and if the upper jaw 248 should be positive in its line of movement the papers might be injured and the operation of the machine impeded. To avoid this, the upper jaw is yielding so 25 that it can deviate to accommodate the variations in the thickness of the papers at their folded edges. As the carriage 240 approaches the magazine, should the jaw 248 strike anywhere between the apexes *a* (Fig. 30 5) of the folds in the two lowest papers it would yield and be guided between the papers. This yielding movement of the jaw is regulated by the screw 254, and the tension spring 256 serves to normally hold the 35 jaw in a horizontal position. For comparatively thick papers, there being a greater distance between the apexes of their folds, the jaw can be given greater play than for thin papers, as the distance between the 40 apexes of the folds in the latter is less. Also, by manipulating the cam-pin 249 the 45 jaw can be regulated to travel in a plane approximately the same as that in which the contacting surfaces of the two lowest papers 50 will generally meet. Any slight deviation from this plane by the meeting surfaces of the papers will be accommodated by the yielding arm. As the carriage 240 continues its movement toward the magazine, the 55 upper jaw 248 passes between the bottom paper and the one immediately above. As the carriage approaches the limit of its stroke the stop 273 engages the pin 271 on the catch 268 and releases the lever 259. 60 When the lever is released the spring 263 forces the jaw 261 upwardly so that its nose 262 closes on the paper and firmly holds the latter against the jaw 248 (Fig. 7). After 65 the lever 259 has been released and the jaws engaged with the paper, the carriage starts

on its movement away from the magazine toward the gripping rolls and carries the paper that has been engaged by the jaws with it. As the paper leaves the magazine and passes beneath the stops 233, it will pass 70 between the presser-feet 238 and the spring-supports 237. The friction of these opposing parts will prevent the papers from being carried forward until the rolls 217 and 218 are brought into engagement. During the 75 movement of the carriage 240 away from the magazine, the roller 266 on the lower end of the lever 259 engages with the cam 270, and thereby depresses the jaw 261 to release the paper. This happens just after the jaws 80 have passed between the gripping rolls 217 and 218, and the edge of the paper is in a position to be grasped by the said rolls. After the jaws have released the paper the carriage continues its movement away from the magazine, and as the paper is held by the presser-feet 238 and the spring-supports 237, the jaws will move clear of the paper. 85 (Fig. 8.) As the carriage approaches the end of its stroke away from the magazine, the free end of the catch 268 engages with the dog 272 and the catch is forced into engagement with the pin 267 to hold the lower end of the lever 259 in an elevated position. 90 Also, as the carriage approaches the limit of its movement, the stop 278 engages with the wing 275 and turns the dog 274 to permit the arm 246 to drop so that the jaws will 95 clear the path of travel of the paper on the return stroke of the carriage. Immediately 100 after the arm 246 drops, the carriage starts on its return stroke toward the magazine. Shortly after it starts this movement the wing 275 strikes the inclined end of the cam 277 and the dog 274 is turned to raise the 105 arm 246 so that the jaws will again be in position to engage with the succeeding paper in the magazine. The paper just released by the jaws will be engaged by the rolls 217 and 218 and moved forward onto the tapes 110 against the stops 197.

When the paper is first introduced between the rolls 217 and 218, the latter are in a raised position, being so held by the action of the cam 224 on the lower end of the 115 hanger 220. As soon as the jaws move clear of the paper, which is held stationary by the presser-feet 238 and the spring supports 237, and drop below the path of travel of the paper and below the tapes 181, the cam 224 will have turned so as to permit the 120 springs 223 to press the rolls 218 onto the paper and into engagement with the rolls 217. The action of the rolls 217 and 218 after engaging with the paper is to draw 125 the latter from the magazine, it having been only partly withdrawn by the jaws, and to feed it onto the tapes 181 against the stops 197. The presser-feet 238 and the spring-supports 237 not only prevent the paper 130

from buckling, but also prevent it from being drawn forward by the tapes and following the jaws after the latter have opened to release it.

5 Should a paper thicker than the one to which the rolls 217 and 218 have been adjusted, where two papers have been folded one inside of the other for an instance, or one thinner, where a paper has parts missing 10 for an example, pass between the gripping rolls, the machine would automatically stop through the action of the upper rolls 218. Should the upper rolls 218 be separated too much from the lower rolls 217 by the too 15 thick paper, or allowed to come too close together by the too thin paper, the ends of the arm 280 and the angular lever 287 would not register, and consequently the operation of the machine would cease, so that the error 20 could be rectified. After the rolls draw the paper from the magazine and feed it onto the tapes, they separate, through the action of the cam-wheel 224, to receive the succeeding paper in the magazine. After the paper 25 is fed onto the tapes 181 by the gripping rolls, it is moved forward until it strikes the fingers 197. The twist in the tapes is such as to cause the paper to move against the longitudinal guide 204, and the latter causes 30 the paper to take the proper direction toward the assembling mechanism of the folding machine. This longitudinal guide can be adjusted relatively to the path of travel of the paper to accommodate papers of different dimensions. The fingers 197 present 35 the edge of the paper squarely to the roll 209 and the collars 182. The finger 207 presses the paper against the tapes and its serrated end, acting as a pawl, prevents the 40 paper from jumping back when it strikes the fingers 197. The shaft 196 is intermittently rocked by the cam 216 to move the fingers 197 to release the paper, and at the same time lower the roll 209 to press the 45 paper onto the collars 182 so that the rotation of the latter will feed the paper to the assembling mechanism.

While the feed mechanism hereinbefore described is particularly adapted to be used 50 with the mailing machine disclosed in my application previously noted, yet it can be used with other machines where a newspaper feed is necessary. Also, the embodiment herein described can be departed from to a 55 considerable extent, and still be within the scope of the invention.

Having thus described my invention, what I claim and desire to secure by Letters Patent is:

60 1. In a feeding mechanism, means for holding the articles in a stack, a carriage reciprocal relatively to said holding means, a jaw pivoted on said carriage, yielding means for guiding said jaw to enter the 65 opening between the edges of two adjacent

articles in the stack, and a jaw co-acting with said pivoted jaw to seize one of the articles.

2. In a feeding mechanism, means for holding the articles in a stack, a yielding jaw for entering between two articles in the stack and a jaw co-acting with said yielding jaw to seize one of the articles, and means for reciprocating said jaws to draw the seized article from the stack. 70 75

3. In a feeding mechanism, means for holding the articles in a stack, a yielding jaw for entering between two articles in the stack and a movable jaw co-acting with said yielding jaw to seize one of the articles, 80 means for actuating said movable jaw to seize the article after the yielding jaw has entered between the articles, and means for reciprocating the jaw to draw the seized article from the stack. 85

4. In a feeding mechanism, means for holding the articles in a stack, a yielding jaw for entering between two articles in the stack and a pivoted jaw co-acting with said yielding jaw to seize one of the articles, 90 means for oscillating said pivoted jaw to seize the article after the yielding jaw has entered between the articles, and means for reciprocating said jaws to draw the seized article from the stack. 95

5. In a feeding mechanism, a magazine having a base provided with a recess and adapted to hold the articles in a stack, a carriage reciprocative relatively to said holding means, a jaw pivoted on said carriage, 100 yielding means for guiding said jaw to enter the opening between the edges of the bottom article in the stack and the one above, and a jaw co-acting with said pivoted jaw for seizing the bottom article. 105

6. In a feeding mechanism, a magazine having a base provided with a recess and adapted to hold the articles in a stack, a yielding jaw for entering between the bottom article in the stack and the one above 110 and a jaw co-acting with said yielding jaw to seize the bottom article, and means for reciprocating said jaws in said recess to draw the seized bottom article from the stack. 115

7. In a feed mechanism, a magazine having a base provided with a recess and adapted to hold the articles in a stack, a yielding jaw for entering between the bottom article in the stack and the one above and a movable jaw co-acting with said yielding jaw to seize the bottom article, means for actuating said movable jaw to seize the bottom article after the yielding jaw has entered between the bottom article and the one above, and means for reciprocating said jaws in said recess to draw the seized bottom article from the stack. 120 125

8. In a feed mechanism, a magazine having a base provided with a recess and adapt- 130

ed to hold the articles in a stack, a yielding jaw for entering between the bottom article in the stack and the one above and a pivoted jaw co-acting with said yielding jaw to seize the bottom article, means for oscillating said pivoted jaw to seize the bottom article after the yielding jaw has entered between the bottom article and the one above, and means for reciprocating said jaws in said recess to 10 draw the seized bottom article from the stack.

9. In a feeding mechanism, means for holding the articles in a stack, rotatable gripping rolls operating to grasp an article 15 to move it forward, a carriage reciprocative intermediate of said holding means and said rolls, a jaw pivoted on said carriage, yielding means for guiding said jaw to enter the opening between the edges of two adjacent 20 articles in the stack, and a jaw co-acting with said pivoted jaw to seize one of the articles to carry it to said rolls.

10. In a feeding mechanism, means for holding the articles in a stack, a yielding jaw for entering between two articles in the stack and a jaw co-acting with said yielding jaw to seize one of the articles, means for reciprocating said jaws to draw the seized 25 article from the stack, and gripping rolls 30 for engaging with the article drawn from the stack and moving it forward.

11. In a feeding mechanism, means for holding the articles in a stack, a yielding jaw for entering between two articles in the stack and a movable jaw co-acting with said yielding jaw to seize one of the articles, means for actuating said movable jaw to seize the article after the yielding jaw has 35 entered between the articles, means for reciprocating the jaws to draw the seized article from the stack, means for actuating said movable jaw to release the article after it has been drawn from the stack, and relatively movable gripping rolls operating to 40 grasp the article as it is released by said 45 jaws to feed it forward.

12. In a feeding mechanism, means for holding the articles in a stack, a yielding jaw for entering between two articles in the stack and a pivoted jaw co-acting with said yielding jaw to seize one of the articles, means for reciprocating the jaws to draw the seized article from the stack, means for oscillating said pivoted jaw to seize the article 50 after the yielding jaw has entered between the articles and also to release the article after it has been drawn from the stack, and relatively movable gripping rolls operating to 55 grasp the article as it is released by said 60 jaws to feed it forward.

13. In a feeding mechanism, a magazine having a base provided with a recess and adapted to hold the articles in a stack, gripping rolls opposite to said recess and operating to grasp an article and to feed it for-

ward, a carriage reciprocative intermediate of said holding means and said rolls, a jaw pivoted on said carriage, yielding means for guiding said jaw to enter the opening between the edges of the bottom article in the 70 stack and the one above, and a jaw co-acting with said pivoted jaw for seizing the bottom article and carrying it to said rolls.

14. In a feeding mechanism, a magazine having a base provided with a recess and 75 adapted to hold the articles in a stack, a yielding jaw for entering between the bottom article in the stack and the one above and a jaw co-acting with said yielding jaw to seize the bottom article, means for reciprocating said jaws in said recess to draw the seized bottom article from the stack, and gripping rolls opposite to said recess to receive the article drawn from the stack to feed it forward.

15. In a feeding mechanism, a magazine having a base provided with a recess and adapted to hold the articles in a stack, a yielding jaw for entering between the bottom article in the stack and the one above 80 and a movable jaw co-acting with said yielding jaw to seize the bottom article, means for reciprocating said jaws in said recess to draw the seized bottom article from the stack, means for actuating said movable jaw 85 to engage the bottom article after the yielding jaw has entered between the bottom article and the one above, means for actuating said movable jaw to release the seized article after it has been drawn from the stack, and relatively movable gripping rolls opposite to 90 said recess and operating to grasp the article as it is released by said jaws to feed it forward.

16. In a feeding mechanism, a magazine having a base provided with a recess and 105 adapted to hold the articles in a stack, a yielding jaw for entering between the bottom article in the stack and the one above and a pivoted jaw co-acting with said yielding jaw to seize the bottom article, means for reciprocating said jaws in said recess to draw the seized bottom article from the stack, means for oscillating said pivoted jaw 110 to seize the bottom article after the yielding jaw has entered between the bottom article and the one above and also to release the article after it has been drawn from the stack, and relatively movable gripping rolls opposite to 115 said recess and operating to grasp the article as it is released by said jaws to feed it forward.

17. In a feeding mechanism, means for holding the articles in a stack, a carriage reciprocative relatively to said holding means, a yielding jaw on said carriage for entering between two articles in the stack and a jaw co-acting with said yielding jaw to seize one of the articles, means for closing the jaws on the article as the carriage approaches the 120 125 130

limit of its stroke toward the holding means and after the yielding jaw has entered between the articles, and means for opening the jaws to release the article as the carriage

5 recedes from the holding means.

18. In a feeding mechanism, means for holding the articles in a stack, a carriage reciprocative relatively to said holding means, a yielding jaw on said carriage for entering 10 between two articles in the stack and a jaw movably mounted on said carriage and co-acting with said yielding jaw to seize one of the articles, means for operating said movable jaw to seize the articles as the carriage 15 approaches the limit of its stroke toward the holding means and after the yielding jaw has entered between the articles, and means for operating said movable jaw to release the article as the carriage recedes from the holding 20 means.

19. In a feeding mechanism, means for holding the article in a stack, a carriage reciprocative relatively to said holding means, a yielding jaw on said carriage for entering 25 between two articles in the stack and a jaw pivoted on said carriage and co-acting with said yielding jaw to seize one of the articles, means for oscillating said pivoted jaw to seize the article as the carriage approaches 30 the limit of its stroke toward the holding means and after the yielding jaw has entered between the articles, and means for oscillating said pivoted jaw to release the article as the carriage recedes from the holding 35 means.

20. In a feeding mechanism, means for holding the article in a stack, a carriage reciprocative relatively to said holding means, a yielding jaw on said carriage for entering 40 between two articles in the stack and a jaw co-acting with said yielding jaw to seize one of the articles, mechanism for adjusting said yielding jaw on said carriage to accommodate articles of different thicknesses, and 45 means for opening and closing said jaws during the reciprocation of the carriage.

21. In a feeding mechanism, means for holding the articles in a stack, a carriage reciprocative relatively to said holding means, 50 a yielding jaw on said carriage for entering between two articles in the stack and a jaw co-acting with said yielding jaw to seize one of the articles, adjustable mechanism for regulating the play of said yielding jaw, and 55 means for opening and closing said jaws during the reciprocation of the carriage.

22. In a feeding mechanism, means for holding the articles in a stack, a carriage reciprocative relatively to said holding means, 60 a yielding jaw on said carriage for entering between two articles in the stack and a jaw co-acting with said yielding jaw to seize one of the articles, adjustable mechanism for regulating the play of said yielding jaw, and 65 mechanism for adjusting said yielding jaw

on said carriage to accommodate articles of different thicknesses, and means for operating said jaws during the reciprocation of the carriage.

23. In a feeding mechanism, means for holding the articles in a stack, rotatable gripping rolls operating to grasp an article to move it forward, a carriage reciprocative between said holding means and said rolls, a jaw pivoted on said carriage, yielding means 70 for guiding said jaw to enter the opening between the edges of two adjacent articles in the stack, a jaw co-acting with said pivoted jaw, and mechanism operating to close said jaws to seize an article as the carriage approaches said holding means and to open said jaws to release the article as the carriage approaches the gripping rolls.

24. In a feeding mechanism, means for holding the articles, rotatable gripping rolls 85 operating to grasp an article to move it forward, a carriage reciprocative intermediate of said holding means and said rolls and passing between said rolls, an arm pivoted on said carriage, co-acting jaws on said arm, 90 mechanism operating to close said jaws to seize an article as the carriage approaches said holding means and to open said jaws to release the article as the carriage approaches said gripping rolls, and mechanism 95 for oscillating said arm to lower said jaws below the path of travel of the article after the jaws have opened and moved clear of the article and to raise the jaws during the return stroke of the carriage toward the holding 100 means.

25. In a feeding mechanism, rotatable gripping rolls operating to grasp an article to move it forward, a carriage reciprocative between said rolls, co-acting jaws on said carriage for seizing an article and moving it between said rolls, mechanism for opening and closing said jaws, and mechanism for moving said jaws out of the path of travel of the article after the jaws have released the article and moved clear of the same, and mechanism for moving said jaws to their original position as the carriage moves away from the gripping rolls.

26. In a feeding mechanism, means for holding the articles, a carriage reciprocative relatively to said holding means, an arm hinged to said carriage, co-acting jaws on said arm, mechanism operating to close said jaws to seize an article as the carriage approaches the holding means and to open the jaws to release the article when the carriage moves away from said holding means, and mechanism for oscillating said arm to lower said jaws below the path of travel of the article after the jaws have opened and moved clear of the article and to raise the jaws during the return stroke of the carriage toward the holding means.

27. In a feeding mechanism, means for

- holding the articles in a stack, a carriage reciprocative relatively to said holding means, an arm hinged to said carriage, a jaw pivoted on said arm, yielding means for 5 guiding said jaw to enter the opening between the edges of two adjacent articles in the stack as the carriage approaches the holding means, a jaw co-acting with said pivoted jaw and operating to seize an article 10 when the carriage approaches the holding means and to release the article when the carriage moves away from the holding means, and mechanism for oscillating said arm to lower said jaws below the path of 15 travel of the article after the jaws have opened and moved clear of the article and to raise the jaws during the return stroke of the carriage toward the holding means.
28. In a feeding mechanism, means for 20 holding the articles in a stack, a carriage reciprocative relatively to said holding means, an arm hinged to said carriage, a pivoted jaw adjustable on said arm to accommodate articles of different thicknesses, yielding 25 means for guiding said jaw to enter the opening between the edges of two adjacent articles in the stack as the carriage approaches the holding means, a jaw pivoted on said arm and co-acting with said adjustable jaw and operating to seize an article 30 when the carriage approaches the holding means and to release the article when the carriage moves away from the holding means, and mechanism for oscillating said 35 arm to lower said jaws below the path of travel of the article after the jaws have opened and moved clear of the article and to raise the jaws during the return stroke of the carriage toward the holding means.
40. 29. In a feeding mechanism, a reciprocative carriage, an arm hinged to said carriage, a pin rotatable in said arm and provided with eccentric bearings, a jaw pivoted on the eccentric bearings of said pin, a second 45 jaw co-acting with the first mentioned jaw, means for opening and closing said jaws, and means for oscillating said arm.
30. In a feeding mechanism, a reciprocative carriage, an arm hinged to said carriage, a jaw pivoted on said arm, a spring normally holding said jaw in a horizontal 50 position, adjustable pins on opposite sides of the pivot of said jaw to regulate the play of said jaw, a second jaw co-acting with the first mentioned jaw, means for operating said jaws, and means for moving said arm.
31. In a feeding mechanism, a reciprocative carriage, an arm hinged to said carriage, a pin rotatable in said arm and provided with eccentric bearings, a jaw pivoted on the eccentric bearings of said pin, yielding 55 means for holding said jaw in an engaging position, a second jaw co-acting with the first mentioned jaw, means for operat-

ing said jaws, and means for oscillating said arm.

32. In a feeding mechanism, a reciprocative carriage, an arm hinged to said carriage, a pin rotatable in said arm and provided with eccentric bearings, a jaw pivoted on the eccentric bearings of said pin, means for regulating the movement of said jaw on said pin, a second jaw co-acting with the first mentioned jaw, means for operating said jaws, and means for moving said arm.

33. In a feeding mechanism, a reciprocative carriage, an arm hinged to said carriage, a jaw on said arm, a lever pivoted to said arm, a jaw on said lever and co-acting with the jaw on the arm, a spring normally pressing the jaw on the lever toward the jaw on the arm, means for moving said lever against the action of said spring, and means for moving said arm.

34. In a feeding mechanism, a guide-way, a carriage reciprocative on said guide-way, an arm hinged to said carriage, co-acting jaws on said arm, means for operating said jaws, a dog pivoted on said carriage and engaging with said arm, a cam on said guide-way for turning said dog to raise said arm, and a stop on said guide-way for engaging with said dog to turn the same to lower said arm.

35. In a feeding mechanism, a guide-way, a carriage reciprocative on said guide-way, an arm hinged to said carriage, a jaw on said arm, a lever pivoted to said arm, a jaw on said lever and co-acting with the jaw on the arm, a spring normally pressing the jaw on the lever toward the jaw on the arm, a latch pivoted on said carriage, a cam on said guide-way to engage with said lever to move the same against the action of said spring and to move the jaw on the lever way from the jaw on the arm, a stop on said guide-way for forcing said latch into engagement with said lever, and a second stop to disengage said latch from said lever.

36. In a feeding mechanism, a magazine for containing the articles in a stack and comprising a base, standards adjustable horizontally on said base, stops vertically 115 adjustable on the front edge of said base, presser-feet carried by said stops, spring-supports on said base co-operating with said presser-feet, and co-acting jaws reciprocative between said presser-feet and spring-supports to engage the bottom article of the stack.

37. In a feeding mechanism, a magazine for containing the articles in a stack and having a recessed base, spring supports on 125 opposite sides of the recess in said base, adjustable presser-feet co-operating with said spring-supports, and co-acting jaws for en-

tering between said spring-supports and presser-feet to engage the bottom article of the stack.

38. In a feeding mechanism, the main driving shaft of the machine, clutch mechanism for transmitting motion to said shaft, a cam-wheel on said shaft having a depression in its periphery, a pivoted lever riding on said cam-wheel and actuated by entering the depression to operate the clutch mechanism to stop the machine, gripping-rolls, a movable frame carrying one of said gripping-rolls and controlled in its movements by the article passing between the gripping-rolls, and a pivoted arm connected with said frame and moved by an article of normal thickness passing through the gripping-rolls to engage said lever to prevent the latter from entering said depression in the cam-wheel.

39. In a feeding mechanism, the main driving shaft of the machine, clutch mechanism for transmitting motion to said shaft,

a cam-wheel on said shaft having a depression in its periphery, a pivoted lever riding on said cam-wheel and actuated by entering the depression to operate the clutch mechanism to stop the machine, gripping-rolls, a movable frame carrying one of said gripping-rolls and controlled in its movements by the article passing between the gripping-rolls, and a pivoted arm comprising relatively adjustable members connected at one end with said frame and moved through the intervening mechanism by an article of normal thickness passing between the gripping-rolls to engage at its other end with said lever to prevent the latter from entering the depression in the cam-wheel.

In testimony whereof, I hereunto affix my signature in the presence of two witnesses.

SINGLETON A. MAXWELL.
